UNITED STATES PATENT OFFICE.

ANTONI LYSIAK, OF MANCHESTER, MASSACHUSETTS.

HORSESHOE.

Application filed October 15, 1921. Serial No. 507,952.

To all whom it may concern:

Be it known that I, ANTONI LYSIAK, a citizen of Poland, residing at Manchester, in the county of Essex and State of Massachusetts, have invented certain new and useful Improvements in Horseshoes, of which the following is a specification.

This invention relates to certain new and useful improvements in horseshoes of that type embodying hinged sections with means for drawing the free ends of the same toward each other so as to efficiently clamp the shoe to the horse's hoof against accidental detachment.

15 The primary object of the invention is to generally simplify and improve horseshoes of the above kind.

Another object of the invention is to provide a horseshoe comprising a rigid lower shoe member with an upper shoe member thereon composed of hinged sections, and simple and efficient means for simultaneously attaching the upper member to the lower member and holding the sections of the upper shoe member against expansion in tight clamping engagement with the horse's hoof.

Other objects will become apparent as the nature of the invention is better understood, 30 and the same consists in the novel form, combination and arrangement of parts herein-after more fully described and shown in the accompanying drawing, in which like characters of reference indicate corresponding parts throughout the several views.

In the drawing,

Figure 1 is a top plan view partly in horizontal section of a horseshoe constructed in accordance with the present invention:

40 Fig. 2 is a side elevational view thereof partly broken away and in section;

Fig. 3 is an enlarged fragmentary sectional view taken substantially upon line III—III of Fig. 1; and

45 Fig. 4 is a view in transverse section along line IV—IV of Fig. 1.

Referring more in detail to the several views, the present invention embodies a lower shoe member 5 of the usual rigid form 50 which may be provided with toe and heel calks 6 and 7 respectively, either of integral or detachable form as desired, although the integral form is shown.

Disposed upon the upper face of the lower 55 shoe member is an upper shoe member composed of a pair of similar half sections 8

and 9 which are hingedly connected at their forward ends as at 10 at the toe portion of the shoe, and which are connected at their lower ends in spaced relation by means for drawing the hinged sections toward each other including a bolt 11 extending through the rear end of the section 8 and having a threaded stem which is screwed into the internally-threaded hollow stem of another 60 bolt 12 which extends through the rear end of the other section 9, the bolts 11 and 12 being provided with spherical heads 13 and 14 respectively engaging hemi-spherical sockets provided in the outer sides of the 65 ends of the sections 8 and 9, said sockets communicating with inwardly extending openings of flaring form, as clearly indicated by dotted lines in Fig. 1, whereby the angular relation between the bolts and the sections may readily vary as is necessary when 70 said sections are adjusted away from or toward each other as the case may be. To provide for the turning of the bolts 11 and 12 so as to adjust the sections 8 and 9, the 75 heads 13 and 14 are provided with screw-driver kerfs 15.

The hinged sections 8 and 9 include a plurality of upwardly and inwardly extending plates 16 preferably formed of sheet 80 metal and having their lower ends rigidly attached to the edges of the sections 8 and 9 by means of screws 17 or the like, the upper ends of the plates 16 being return-bent in tubular form to provide eyes 16' 85 through which a flexible member 18, such as resilient wire, is threaded, said flexible member 18 being in two sections with adjacent outturned ends 19 formed into eyes through which a bolt 20 extends, the bolt 20 having 90 a nut 21 threaded thereon for drawing the sections of the flexible member toward each other into tight engagement with the horse's hoof. It will also be noted that the plates 16 of each section 8 and 9 greatly increase 95 in height from the rear of the shoe to the front of the same, whereby said plates will be given a large surface of engagement with the horse's hoof at the point where the same is most needed. The usual upwardly-di- 100 rected toe-lug 22 may be provided to form an abutment in positioning the shoe upon the horse's hoof, while the rear ends of the sections of the flexible member 18 are bent downwardly and suitably secured in openings which are provided at an incline in the sections 8 and 9, as at 23.

The hinged sections 8 and 9 of the upper shoe member are provided intermediate their ends with a slightly arcuate series of internally-threaded openings 24 which are approximately concentric with the pivot 10, and the shoe member 5 is provided with an opening 25 in alignment with each series of openings 24 for reception of a bolt 26, the lower portion of the opening 25 at each side 10 of the shoe being enlarged for reception of the head of the bolt 26 positioned therein and the shank of the bolt 26 is of such length as to be threaded into a desired one of the adjacent series of openings 24 so as to hold 15 the upper shoe member onto the lower shoe member no matter in what adjustment the sections 8 and 9 may be relative to each other. These screws 26 also assist the bolts 11 and 12 in retaining the sections 8 and 20 9 against spreading when the shoe is operatively disposed upon the horse's hoof. The depth of the enlarged lower portion of each opening 25 is greater than the thickness of the head of each bolt 26, and the 25 wall of the enlarged portion is threaded for reception of a removable set-screw 27 which covers the head of the bolt 26. Each bolt 26 is provided with a screwdriver kerf in the head of the same for adjustment thereof and this is also true with respect to the 30 set-screws 27. In this way, the set-screw 27 must be removed before the bolt 26 can be removed, and the set-screws 27 prevent accidental backward turning of the screws 26. 35 From the foregoing description, it is believed that the construction and operation of the present invention as well as the advantages thereof will be readily understood and appreciated by those skilled in the art. 40 Minor changes may be made therein without departing from the spirit and scope of the invention as claimed.

What is claimed as new is:

1. A horseshoe comprising a rigid lower shoe member, an upper shoe member resting thereon composed of a pair of half sections hingedly connected at their forward ends and having means for engaging a horse's hoof to clamp the shoe in position upon movement of the sections toward each other, and means for adjustably attaching the upper shoe member to the lower shoe member while permitting relative movement between said hinged sections.
- 45 2. A horseshoe comprising a rigid lower shoe member, an upper shoe member resting thereon composed of a pair of half sections hingedly connected at their forward ends and having means for engaging a horse's hoof to clamp the shoe in position upon movement of the sections toward each other, means for adjustably attaching the upper shoe member to the lower shoe member while permitting relative movement between said hinged sections, and means associated
- 50
- 55
- 60
- 65

with the rear ends of said hinged sections for drawing the same toward each other.

3. A horseshoe comprising a rigid lower shoe member, an upper shoe member resting thereon composed of a pair of half sections hingedly connected at their forward ends and having means for engaging a horse's hoof to clamp the shoe in position upon movement of the sections toward each other, and means for adjustably attaching the upper shoe member to the lower shoe member while permitting relative movement between said hinged sections, said last-named means comprising screws carried by the sides of the lower shoe member, and the sections of the upper shoe member being provided with an arcuate series of internally threaded openings for screw-threaded engagement with each screw selectively.

4. A horseshoe comprising a rigid lower shoe member, an upper shoe member resting thereon composed of a pair of half sections hingedly connected at their forward ends and having means for engaging a horse's hoof to clamp the shoe in position upon movement of the sections toward each other, means for adjustably attaching the upper shoe member to the lower shoe member while permitting relative movement between said hinged sections, said means for clamping engagement with the horse's hoof including a plurality of upwardly projecting plates attached rigidly to the outer edges of the hinged sections and having their upper ends return-bent in tubular form to provide alined eyes, and a flexible member having its ends attached to the heel portions of the upper shoe member and threaded through said eyes of the plates.

5. A horseshoe comprising a rigid lower shoe member, an upper shoe member resting thereon composed of a pair of half sections hingedly connected at their forward ends and having means for engaging a horse's hoof to clamp the shoe in position upon movement of the sections toward each other, means for adjustably attaching the upper shoe member to the lower shoe member while permitting relative movement between said hinged sections, said means for clamping engagement with the horse's hoof including a plurality of upwardly projecting plates attached rigidly to the outer edges of the hinged sections and having their upper ends return-bent in tubular form to provide alined eyes, a flexible member having its ends attached to the heel portions of the upper shoe member and threaded through said eyes of the plates, and means to adjust the length of said flexible member for more tightly engaging the plates with the horse's hoof.

6. A horseshoe comprising a rigid lower shoe member, an upper shoe member resting thereon composed of a pair of half sections

hingedly connected at their forward ends and having means for engaging a horse's hoof to clamp the shoe in position upon movement of the sections toward each other, 5 means for adjustably attaching the upper shoe member to the lower shoe member while permitting relative movement between said hinged sections, said means for clamping engagement with the horse's hoof including a plurality of upwardly projecting plates attached rigidly to the outer edges of the hinged sections and having their upper ends return-bent in tubular form to provide aligned eyes, and a flexible member having its ends attached to the heel portions of 15 the upper shoe member and threaded through said eyes of the plates, said plates being greatly decreased in length from front to rear of each hinged section.

In testimony whereof I affix my signature. 20

ANTONI LYSIAK.
